(57) **CLAIM**

The ornamental design for a hybrid aerial vehicle, as shown and described.

DESCRIPTION

FIG. 1 is an isometric view of a hybrid aerial vehicle showing our new design.

FIG. 2 is a front perspective view.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.

The broken lines in the figures depict portions of the hybrid aerial vehicle that form no part of the claimed design.

1 Claim, 6 Drawing Sheets
